(57) **CLAIM**

The ornamental design for an analyte measurement apparatus, as shown and as described.

DESCRIPTION

FIG. 1 is a perspective view of an analyte measurement apparatus according to the present design;

FIG. 2 is a front view of the analyte measurement apparatus according to the present design;

FIG. 3 is a rear view of the analyte measurement apparatus according to the present design;

FIG. 4 is a left side view of the analyte measurement apparatus according to the present design;

FIG. 5 is a right side view of the analyte measurement apparatus according to the present design;

FIG. 6 is a top view of the analyte measurement apparatus according to the present design; and,

FIG. 7 is a bottom view of the analyte measurement apparatus according to the present design.
